Fig. 5

Fig. 6

Fig. 7

FIG. 1 is a perspective view of an atomizing head for an electrostatic sprayer showing our new designs;

FIG. 2 is a rear elevational view thereof;

FIG. 3 is a left side elevational view thereof;

FIG. 4 is a front elevational view thereof;

FIG. 5 is a right side elevational view thereof;

FIG. 6 is a bottom elevational view thereof; and

FIG. 7 is a top elevational view thereof.

The broken lines in FIG. 1 are for illustrative purposes only.

We claim:

The ornamental design for an atomizing head for an electrostatic sprayer, substantially as shown and described.
